(57) **CLAIM**

The ornamental design for a bracket, as shown and described.

DESCRIPTION

FIG. 1 is a top perspective view of the bracket of the invention;

FIG. 2 is a top plan view of the bracket;

FIG. 3 is a view in elevation of the bracket from the front side;

FIG. 4 is a view in elevation of the bracket from the left side, the view in elevation of the bracket from the right side being a mirror image thereof;

FIG. 5 is a view in elevation of the bracket from the rear side; and,

FIG. 6 is a bottom plan view of the bracket.

The claimed design is shown broken away to indicate indeterminate length.
